(Continued)

Primary Examiner — Ryan Harvey(74) *Attorney, Agent, or Firm* — Banner & Witcoff, Ltd.(57) **CLAIM**

The ornamental design for a gaming terminal, as shown and described.

DESCRIPTION

FIG. 1 is a front perspective view of a gaming terminal showing our new design;

FIG. 2 is a front perspective view of a second embodiment of a gaming terminal showing our new design;

FIG. 3 is a front perspective view of a third embodiment of a gaming terminal showing our new design; and,

FIG. 4 is a front perspective view of a fourth embodiment of a gaming terminal showing our new design.

The broken lines depicting the remainder of the gaming terminal show features that form no part of the claimed design.

1 Claim, 4 Drawing Sheets(56)
